TAP GRINDING MACHINE

Edd C. Oliver, Adrian, Mich.

Application January 15, 1931, Serial No. 509,000

14 Claims. (Cl. 51—101)

This invention relates to machines for grinding taps, it being a purpose of the invention to provide a machine that is adjustable to adapt the same for grinding not only the ordinary tapered tap but other special forms as a plug tap, a gun tap, a bottoming tap, etc.

It is further an object of the invention to provide a tap grinder of such character that two, three or four lipped taps may be automatically ground to form—that is, providing the proper taper at the entering end depending upon the type of the tap and grinding the lip back of the cutting edge to provide clearance in operation.

Further features of the invention are involved in the means for causing the automatic grinding of the lip to a predetermined extent back of the cutting edge and in the means whereby a tap of any number of lips may be ground automatically.

20 A further feature and object of the invention is to provide a tap grinding machine that is adjustable for use with any size or diameter of tap in which the lip at its entering end is ground to any desired taper as is required for the purpose for which the tap is to be used and further it is a purpose of the invention to provide a machine that may be adjusted for use in dressing the cutting face of a lip and that is comparatively simple and inexpensive in form.

30 These and other objects and the several novel features of the invention are hereinafter more fully described and claimed, and a tap grinding machine embodying my invention is shown in the accompanying drawings in which—

35 Fig. 1 is a side elevation of the machine.

Fig. 2 is a front elevation thereof.

Fig. 3 is a plan view.

Fig. 4 is an enlarged section taken on line 4—4 of Fig. 3.

40 Fig. 5 is an enlarged section taken on line 5—5 of Fig. 3.

Fig. 6 is an enlarged section taken on line 6—6 of Fig. 3.

Fig. 7 is a side elevation of a bottoming tap.

45 Fig. 8 is an end view thereof.

Fig. 9 is a side elevation of a plug tap.

Fig. 10 is an end view thereof.

Fig. 11 is a side elevation of a tapered tap.

Fig. 12 is an end view thereof.

50 Fig. 13 is a side elevation of a gun tap.

Fig. 14 is an end view thereof.

Fig. 15 is a diagram showing the relation of the gauge or stop in positioning the tap for the grinding operation.

55 Fig. 16 is a perspective view of the head of the

machine illustrating the relationship of the parts in the grinding operation.

Fig. 17 is an enlarged section taken on line 17—17 of Fig. 1.

Fig. 18 is a cross section taken on line 18—18 of Fig. 2.

Fig. 19 is a vertical section taken on line 19—19 of Fig. 2.

Fig. 20 is a vertical section taken on line 20—20 of Fig. 5.

A screw shaft 15 is threaded in a nut 13a secured in a longitudinal aperture 13b in the member 13 and the base portions 16 and the clamping member 17 have an attached plate 17a engaging a collar 17b on the screw shaft whereby rotation of the screw shaft by the hand wheel 18 causes the carriage 14 to be moved toward or from the pedestal on the member 13.

The carriage 14 has a slide or table 19 movable longitudinally thereof by means of a screw shaft 20 provided with a hand wheel or crank 21 which is rotatably secured in the attached flange 19a of the table 19 whereby rotation of the shaft causes longitudinal movement of the table. The slide 19 has tapered side flanges 22 engaging complementary edges of the carriage 14. The carriage 14 has a nut 23 at one end into which the threaded shaft extends, and a nut 24 at the other end thereof permitting the screw shaft to be mounted at either end of the carriage.

Rotation of the hand lever 21 causes movement of the table 19 longitudinally of the carriage 14 at a right angle to the direction of movement of the carriage 14 by the screw 15. The table 19 has a raised circular boss portion 25 thereon formed with a finished face to receive the circular plate 26. This plate is centrally apertured to receive the screw 27, which extends through the plate 26 into a threaded aperture in the portion 25 on the table 19. As will be seen in Fig. 1 the boss 25 extends outwardly on one side of the table 19 and the two parts 25 and 26 are calibrated as at 28 for the purpose herein-after stated. The part 26 is rotatable on the screw 27 and by loosening the screw the member 26 and parts carried thereby, (hereinafter described), may be turned at any angle desired which may be determined by the calibrations 28. This portion 26 above described is formed with an extension or base 29 which is spaced above the table as will be seen in Fig. 2 and is provided with an aperture in the outer end thereof to receive a shaft 30 shown clearly in Fig. 4. This shaft 30 is secured in the aperture of the base 29 as by means of a set screw 31 which holds the

same from rotation and from longitudinal movement. The shaft extends outwardly from this base member 29 and a head 32 is rotatably supported thereon. In this head is a spindle 33 supported in anti-friction bearings 34 and 35 positioned in opposite ends respectively of the head. The spindle 33 has a coned forward end 36 and within this spindle is a sleeve 37 having a coned face to seat in the coned end 36 of the spindle and a threaded end portion 38 to receive the chuck 39. The sleeve 37 may have its coned end portion clamped in the coned end portion of the spindle 33 by means of the hand nut 40 at the outer end thereof. The spindle 33 also is provided with a nut 41 for holding the same from longitudinal movement in the bearings. Also adjacent this nut 41 and secured to the spindle is an index plate 42 having notches 43 in its face to receive the pawl 44 which is pivoted at 45 to the head 32. Between this index plate 42 and the end of the head is a cylindrical cover member 46 for the spiral gear 47 which is secured to the spindle 33. A worm 48 engages the spiral gear and is supported in a casting 49 pinned or secured to the outer end of the fixed shaft 30 and the worm may be operated by the handle 50. The head 32 is formed of a base on the shaft 30 and two upwardly extending portions 51 and 52 at opposite ends which are recessed to receive the bearings 34 and 35 and on the spindle 33 between these portions 51 and 52 of the head are a series of cams 53, 54, 55 and 56 which are in spaced relation longitudinally of the spindle. The cams 53, 54 and 55 are of a shape for use with two, three and four lipped taps respectively and the remaining cam 56 may be of any special shape as might be required for a special shape of clearance or other difference in form required for some special purpose. It is to be noted that this head and all the parts carried thereby including the spindle, index plate, spiral gear, chuck and the tap carried thereby are supported by the head 32 and thus all of these parts may oscillate as a unit on the shaft 30. As will be seen more clearly in Fig. 6 the base 29 has a square shaft 57 secured therein extending outwardly parallel with the shaft 30, it being secured in the base 29 as by means of a screw 58 shown by dotted lines in Fig. 6. On this square bar 57 is slidably mounted a frame 59 at the upper end of which is carried a roller 60 flanged to engage over opposite sides of a cam and thus when positioned in engagement with any cam of the group it is held from displacement by these flanges. It will be observed more clearly in Fig. 3 that the flanges 61 of the roller extend into the spaces between the cams of which three only are shown in this figure. As these cams are carried by the rotatable head means is provided to cause the cams to lie in pressure engagement with the roller. This means consists of a plunger 62 supported in a recess 63 provided in a portion 64 of the head and a spring 65 tends to project this plunger downwardly from the recess. The base 29 has a portion 66 projecting outwardly therefrom parallel with the shaft 30 with which the plunger engages and as this plunger engages a fixed part 66 on the base 29 and the roller 60 is carried by a part also supported by the base 29 on the opposite side of the shaft 30 the cams will be held in contact with the roller under pressure. The tap is supported in the chuck in the usual manner and if an ordinary tap is to be ground

it is positioned relative to the grinding wheel 5 substantially as indicated in Figs. 15 and 16. The tap shown in Figs. 15 and 16 is an ordinary right hand tap and to position the tap with the cutting edge in proper relation with the grinding wheel I provide a gauge 67 which has at its upper end the cut away portion 68 on the center line of the machine and on its opposite side has a hanging lip 69 the under face of which is also on the center line of the machine. As shown in Fig. 4 the gauge is mounted on the plate 70 formed with a slot 71 to receive a fastening screw 72. This base permits the gauge to be turned at any angle about the screw and is variable in its distance from the screw center. The gauge 67 has a threaded end portion 73 extending through an aperture provided in the end of the plate 70 and a nut 74 secures the same in place.

In operating the machine to grind a four lipped right hand tapered tap, the tap is first mounted in the chuck and clamped by the shank the same as it is held in the tapping machine. When the tap has been clamped the hand nut or knob 40 is locked and the chuck revolved about its axis until the cutting edge of a lip of the tap rests on the cut away portion 68 of the gauge 67. With the left hand tap the cutting edge will be in the reverse position from that shown in Fig. 15 and is brought in contact with the under side of the flange 69 of the gauge.

In either case the cutting edge of the opposite lip of the tap is exactly at the center height of the axis of rotation. When this adjustment has been completed the latch 44 is dropped in the index plate at a designated notch marked "zero" (not here shown) and the hand nut 40 then clamped tightly to maintain the tap in that position. The roller 60 is then brought opposite the cam corresponding to the number of cutting edges of the tap to be ground (in the above case cam 53) and it is to be understood that these cams are formed with two, three or four high points depending upon the number of lips with which the tap is provided, the cam 55 for the four-lipped tap being shown in Figs. 6 and 15 as having the high points *a*, *b*, *c*, and *d*. The spindle is then revolved by rotation of the screw 48 and thus the cam will roll against the roller producing an oscillating motion of the head 32 and the parts carried thereby including the tap. Due to the position of the cutting edge of the lip of the tap with the wheel shown in Fig. 15, this oscillating motion causes the top to move toward the vertical face of the wheel which therefore grinds an eccentric relief from the cutting edge of the lip backwardly depending upon the contour of the cam.

The base 29 being swiveled on the bolt 27 permits any degree of taper at the point of the tap as may be required either with the ordinary tap, plug or bottoming taps. The carriage 14 can be moved longitudinally to bring the tap on any desired part of the grinding wheel below the center line thereof. Rotation by the handle 50 brings the successive lips of the tap to be ground in strict relation with the oscillatory movement caused by the cam wheels, the gauge 67 during the grinding operation being moved out of position.

The above description has been closely confined to the mechanism and arrangement of parts for grinding the ordinary right hand four-lipped tap, but, as will be evident from the foregoing and by use of the proper cam wheel, taps with different numbers of lips may be automatically ground with

the correct or desired relief or clearance back of the cutting edge and by variation of the base 29 about its axis and through or by means of the calibrations 28 the lips may be ground with any degree of taper as may be required for the different forms of taps. With the three-lipped gun tap shown in Fig. 13, the entering end of the tap may be taper ground after the manner described above relative to the four-lipped tap; but with this type of tap the cutting face of the lip at the entering end of the tap is usually ground at an angle to the longitudinal axis of the tap as indicated at 70 in Fig. 13 providing a means for forcing the chips upwardly in the flute of the tap.

15 It will further be realized from the foregoing that the machine is so constructed as to permit adjustment of the tap for operation on the under side of the periphery of the grinding wheel or in grinding relation with the corner between 20 the vertical and peripheral face of the wheel. When adjusted as last stated and while the tap is held from rotation or oscillation of the table 19 by means of the screw 21 causes movement of the tap in a straight line across the face of the wheel whereby the cutting face of the lip may be ground on a straight line or the tap may be positioned at such angle to permit the grinding of the face of the lip at an angle as indicated at 25 70 in Fig. 13. In this latter case the tap and the head therefor are held from oscillatory or rotative movement of the tap. The machine therefore is so constructed as to adapt the same for the grinding of any portion of the tap in the desired manner, even for the purpose of grinding off the end 30 of the tap at a right angle to its axis. This latter result may be attained by swinging the table 19 at a right angle to the position shown in Fig. 2 with the axis of the table parallel with the axis of the grinding wheel and by operation of the 35 screw 18 move the table 19 bringing the end of the tap into grinding relation with the wheel.

It will thus also be evident from the foregoing that the various objects of the invention are attained by the described mechanism.

40 Having thus fully described my invention, what I claim and desire to secure by Letters Patent of the United States is—

1. In a machine for grinding taps having a plurality of lips, a rotatable grinding wheel, a tap holder, a pivoted base supporting the tap holder, means for adjusting the base about its pivot to thereby position the holder with the longitudinal axis of the tap at the desired angle to the face of the wheel, means for varying the position of 45 the pivot point of the base to position a desired length of the tap for engagement with the wheel face, manual means carried by the base for turning the tap to bring the lips thereof in succession to grinding relation with the wheel, and means whereby each lip is ground to an increasing extent rearwardly of the cutting edge to provide 50 clearance.

2. In a machine for grinding taps having a plurality of lips, a rotatable grinding wheel, a tap holder, a pivoted base supporting the holder, means for adjusting the base about its pivot to position the tap with the lip thereof for grinding 55 relation with the wheel, means for varying the position of the pivot point of the base to present a greater or less length of the tap for the grinding operation, and means for moving the holder during the grinding of the tap toward the grinding wheel whereby the lip is ground eccentrically to the axis of the tap to provide clearance.

70 3. In a machine for grinding taps having a plu-

rality of lips, a rotatable grinding wheel, a tap holder, a pivoted base for the holder, means for adjusting the base about its pivot to position the tap in grinding relation with the wheel, means for varying the position of the pivot point of the base relative to the axis of rotation of the wheel to position the desired length of the tap for engagement with the wheel face, means for rotating the tap whereby the lips thereof are brought successively to the grinding relation with the wheel, means actuated by the means for rotating the tap to move the holder as each lip comes to grinding position toward the grinding wheel to cause the face of the lip to be ground eccentrically to the axis of the tap to provide clearance.

4. In a machine for grinding taps having a plurality of lips, a rotatable grinding wheel, a tap holder, a pivoted base supporting the holder, manually operable means for rotating the tap to bring successive lips thereof to grinding relation with the wheel, means for adjusting the pivot point of the base to vary the length of the tap to be submitted for the grinding operation, a cam supported by the holder on the axis of rotation of the tap and operable through rotation thereof to move the holder toward the grinding wheel as each lip of the tap comes to grinding position and thereby cause the face of the lip to be ground eccentrically to the axis of the tap to provide clearance.

5. In a machine for grinding taps having a plurality of lips, a rotatable grinding wheel having a flat face, a tap holder, manual means for rotating the holder to bring the lips of the tap successively to grinding relation with the face of the grinding wheel, means acting automatically through rotation of the holder to move the holder and tap toward the grinding wheel as each lip thereof is brought to grinding relation therewith to cause the face of each lip to be ground eccentrically to the axis of the tap, a pivotal support for the holder permitting adjustment to vary the angle of presentation of the tap to the grinding wheel, a slide for said pivotal support whereby the pivotal point for the holder may be varied in position toward or from the axis of rotation of the wheel whereby the length of the tap to be ground may be determined by the angle of presentation of the tap to the wheel.

6. In a machine for grinding taps having a plurality of lips, a rotatable grinding wheel having a flat face, a tap holder, a pivotal base supporting the holder, a shaft carried by the base on which the holder is mounted for oscillation, manual means for rotating the holder and tap, means automatically operating by rotation of the holder to cause an oscillation thereof on the shaft in timed relation with the rotation whereby each lip of the tap is moved into the face of the grinding wheel to an increasing extent back of the cutting edge to provide clearance, said pivoted base providing a means for varying the angle of presentation of the tap to the face of the wheel, a slide on which the base is pivotally mounted, and means for moving the slide whereby the length of the tap to be presented to the grinding wheel may be varied.

7. In a machine for grinding taps having a plurality of lips, a rotatable grinding wheel, a tap holder, a pivoted base supporting the same and adapted to be adjusted to position the tap at any desired angle to the face of the wheel, means for moving the pivot point of the base to thereby move the tap longitudinally toward or from the wheel to the necessary position for the grinding

- operation and to determine the length of the face of the lip to be ground, means for indexing the tap, means for rotating the same whereby successive lips are brought to grinding position, and 5 automatic means for causing the tap to move into the face of the wheel as each lip is being ground causing the same to be ground to an increasing extent back of the cutting edge to provide clearance.
- 10 8. In a machine for grinding taps having a plurality of lips, a rotatable grinding wheel having a flat face, a tap holder, a head in which the holder is rotatable, a pivoted base supporting the head turnable to position a tap at any predetermined angle to the said face of the wheel, means for moving the pivot point of the base transversely of the axis of rotation of the grinding wheel to thereby determine the length of the face of the lip to be ground means for causing continuous rotation of the holder whereby the lips of the tap are brought in succession to grinding relation with the wheel, a cam on the holder rotatable in fixed relation therewith, said cam having a number of high points corresponding to the number 25 of lips of the tap, and an element fixed in position engaged by the cam to cause an oscillatory movement of the holder toward and from the wheel in timed relation with the rotation of the tap to cause a feed-in movement of the tap toward the grinding wheel as each lip is brought to grinding relation to thereby cause the tap to be ground to an increasing extent back of the cutting edge.
9. In a machine for grinding taps having a plurality of lips, a rotatable grinding wheel having a flat grinding face, a tap holder, a head in which the holder is rotatable, a base for supporting the head and relative to which the head is oscillatable, said base being movable about an axis to position a tap at any predetermined angle 35 to the said face of the grinding wheel and the axis of which is movable at a right angle to the axis of rotation of the wheel to thereby present a greater or less length of the tap to the wheel, means for causing rotation of the holder whereby the lips of the tap are brought in succession to grinding relation with the wheel, a cam rotatable through rotation of the holder on the same axis and having a number of high and low points in 40 succession corresponding to the number of lips of the tap, means for adjusting the tap with the cutting face of the lip in the necessary relation with a high point of the cam, a fixed element supported by the base with which the cam engages whereby rotation of the cam causes oscillation of 45 the head in a manner to cause the tap to move toward the wheel as each lip is brought to grinding relation to thereby cause the lip to be ground to an increasing extent back of its cutting edge.
10. In a machine for grinding taps having a plurality of lips, a rotatable grinding wheel, a tap holder, a head in which the holder is rotatably mounted, means for rotating the holder, a base supporting the said holder in a manner to permit the same to oscillate about the axis of 55 rotation of the holder, said base being pivotally mounted to permit the positioning of the tap at the desired angle to the grinding wheel, means for moving the pivot point to thereby present a greater or a less length of the tap from its point 60 toward its shank to the grinding wheel a series of cams each having a number of high points corresponding to the number of lips of the tap, said cams being rotatable through rotation of the holder and on the same axis, an element 65 adapted to be brought to cooperative relation with any one of the cams, the arrangement of the cams and said element and the head being such that rotation of the cams causes an oscillation of the head, means for adjusting the holder whereby the cutting edge of each lip is in a predetermined relation with the high points of its cam, means for rotating the holder and tap to bring successive lips thereof to the grinding relation with the wheel, the face of the cam having a curve extending from each low to each high point eccentric to the axis of rotation thereof and so positioned relative to the tap and said element cooperative with the cam that the tap is moved away from the grinding face of the wheel as a lip comes to grinding position and thereupon as the high point of the cam passes the said element, the said lip is moved into the face of the grinding wheel to grind the said lip eccentrically to its axis of rotation and to an increasing extent back of the cutting edge, and yieldable means 75 for holding the cam in contact with said element.
11. In a machine for grinding taps having a plurality of lips, a rotatable grinding wheel having a vertical grinding face, a rotatable tap holder, a base supporting the holder and pivoted to swing on a vertical axis to position the tap at a desired angle to said grinding face of the wheel, means for variably positioning the pivot point of the base to vary the length of the tap to be presented to the grinding wheel, a cam on the holder and rotatable therewith on the same axis, said cam having a series of high and low points each in number equal to the number of lips of the tap and the shape of the face of the cam from each high to each low point being an arc 85 eccentric to the axis of rotation, means for positioning the lips of the tap in the necessary relationship to the high and low points of the cam, means whereby rotation of the cam causes an oscillation of the tap and holder toward and from the grinding face of the wheel, the arrangement being such that as each lip is brought to grinding position, the arcuate face from a high toward a low point of the cam causes the tap to move toward the wheel as it is rotated and thus 95 grind the said lip back of the cutting edge eccentrically to its axis of rotation.
12. In a machine for grinding taps having a plurality of lips, a rotatable grinding wheel, a tap holder a pivoted base therefor, means for adjusting the pivot point of the base to position the tap relative to the wheel, means for rotating the holder and tap to bring successive lips supported by the holder and rotatable on the 100 same axis as the tap, said cam having a series of high and low points each equal in number to the number of lips of the tap and the shape of the face from the cam from each high to each low point being an arc eccentric to the axis of 105 rotation, means for positioning the tap with the lips thereof in the necessary relationship to the high and low points of the cam, means whereby rotation of the cam causes an oscillation of the holder and tap toward and from the grinding 110 position whereby as each lip of the tap is turned to grinding position the tap is caused to move toward the wheel to grind the lip to an increasing extent back of the cutting edge to provide clearance, the shape of the cam and the tap adjusting mechanism adapting the machine for use in the grinding of either a right or left hand tap substantially as described.
13. In a machine for grinding taps having a plurality of lips, a rotatable grinding wheel, a 115

rotatable tap holder a pivotal support therefor, power means for rotating the grinding wheel, manual means for rotating the holder, a cam having a series of high and low points each corresponding in number to the number of lips of the tap, the shape of the face of the cam from each high to each low point being an arc eccentric to the axis of rotation, means for positioning the cam with the points thereof in correct relationship to the lips of the tap at the time the tap is in gauging position, means for automatically causing an oscillation of the tap toward and from the grinding wheel whereby as each lip is brought to grinding position it is caused to feed into the wheel as it reaches grinding position and thus grind a clearance back of the cutting edge of each lip, means for adjusting the pivotal support to thereby position the tap longitudinally relative to the grinding wheel whereby the grinding operation is performed upon a desired part of the tap, and means for adjusting the position of the tap angularly relative to the surface of the grinding wheel comprising a pivotally mounted base supporting the holder,

25

cams and related parts, and means for causing engagement of the tap and grinding wheel while the tap and related parts are held from oscillatory movement.

14. In a machine for grinding taps having a plurality of lips, a grinding wheel having a flat face, a frame member for supporting the wheel, a base member pivotally supported on the frame member, means for varying the pivotal position of the base a tap holder supported on the base in a manner to permit oscillatory movement about a horizontal axis, a cam supported by the oscillatory member and rotatable on the axis of the tap and holder at the same speed of rotation, operating means for rotating the tap holder and cams also carried by the base, means supported by the pivoted base and engageable by the cam to cause the holder to oscillate and thereby move the tap toward and from the grinding wheel in such manner that each lip thereof is ground to an increasing extent back of the cutting edge to provide clearance. 80 85 90 95
